UNITED STATES PATENT OFFICE

WILLIAM E. CAFFRAY, OF NASHUA, NEW HAMPSHIRE, ASSIGNOR TO NASHUA MANUFACTURING COMPANY, OF NASHUA, NEW HAMPSHIRE, A CORPORATION OF NEW HAMPSHIRE

MACHINE FOR DYEING FABRICS

Application filed October 1, 1928. Serial No. 309,532.

This invention relates to machines and apparatus for dyeing fabrics.

In the usual method of vat dyeing the color or dye is applied to the goods in a reduced condition and in an alkaline solution in order to make the dye adhere to the fibre of the goods. In applying certain colors, as for example, indanthrene blues, to some goods, particularly certain grades of cotton fabrics, it is difficult to obtain the desired degree of penetration of the dye. The present invention deals especially with this problem. It aims to improve the machines for dyeing fabrics with a view to handling the goods rapidly and economically, while at the same time producing a more satisfactory penetration of the dye than has been possible heretofore.

In a typical vat dyeing process the dye is reduced by sodium hydrosulphite and is applied to the goods in a caustic soda solution. After the fabric has been run through the dye bath it is then washed with water, the dye is oxidized as by running it through a bath of potassium bichromate or other oxidizing agents, the goods are again washed, given a usual soaping treatment, and then given a final washing and drying. It is contemplated that the machine provided by this invention may be used in one or more of these steps which are collateral to or go with the main step of applying the dye stuff to the cloth, or in the application of direct or other dyes to the goods, although the problem of penetration is not usually as troublesome here as with vat dyes. The term "dye" or "dye bath", therefore, will be used herein to designate the liquid used in the machine, whether or not it is a dye stuff or one of the liquids or solutions used in an operation collateral to dyeing.

The nature of the invention will be readily understood from the following description when read in connection with the accompanying drawings, and the novel features will be particularly pointed out in the appended claims.

In the drawings,

Figure 1 is a side view of a machine embodying this invention;

Fig. 2 is a fragmentary sectional view of the machine shown in Fig. 1;

Fig. 3 is an end view of a portion of the machine shown in Fig. 1, certain of the parts being broken away in order better to illustrate the construction; and

Fig. 4 is a sectional view of a modification.

According to the preferred practice, a web of cloth is fed continuously through a dye bath and the bath is sucked through the cloth while it is submerged in the dye and is moving through it. If the dye bath is made of the proper consistency, which can readily be done by suitably proportioning the liquid and solid constituents of the bath, as will be obvious to anyone skilled in this art, the suction will result in producing a good penetration of the bath through the fibre of the goods.

The machine shown in the drawings comprises a tank 2 adapted to hold a quantity of dye bath and preferably provided with a jacket 3 through which steam can be circulated to maintain the bath at the desired temperature. Mounted in the tank 2 is a roll 4 which revolves idly and two suction tubes 5 and 6, respectively, are mounted just above the roll and parallel with it. Each of these tubes has a narrow slot in one side thereof, as best shown in Fig. 4, this slot extending for nearly the entire length of the tube. Pipes 7 and 8 connect the tubes to the intake end of a rotary exhaust pump 9 which is mounted at one side of the tank and serves to maintain a strong vacuum in both of the tubes 5 and 6.

The liquid "color" or dye bath may be delivered to the tank 2 in any convenient manner, and an overflow pipe 10, Fig. 3, is provided to limit the maximum level of the dye bath in the tank, the upper end of this pipe being located at a somewhat higher level than the tubes 5 and 6. Immediately above the tank 2 two squeeze rolls 14 and 15 are provided, the shaft of the lower roll 14 being equipped with a pulley 16 by means of which the rolls may be driven. In order to apply pressure to the fabric passing between the rolls the upper roll 15 is supported in two levers 17-17, Figs. 1 and 3, which are connected by upright links 18-18 to approxi-

mately horizontal levers 19—19 fulcrumed on the machine frame. Weights 20—20 are adjustably mounted on the latter levers and operate through the links 18 and levers 17 5 to press the upper roll 15 against the lower roll 14.

Chains 21—21 are connected to the levers 19—19 and run over drums 22—22 both mounted fast on a shaft 23 which is journaled in the upper part of the machine frame. Ratchets 24—24 are associated with the respective drums and each ratchet has a pawl or dog 25 to cooperate with it. A hand wheel 26 is mounted on the shaft 23 and by turning this hand wheel the chains 21—21 may be partly wound on their respective drums, thus lifting the levers 19—19 and raising the upper squeeze roll 15 away from its cooperating roll. The dogs 25—25 cooperate with 15 their respective ratchet wheels to lock the upper roll in its elevated position. This mechanism is desirable to facilitate the threading of the web through the machine and for other purposes.

25 The web of cloth W to be dyed may be drawn from a box, truck, or any convenient source, and usually is fed through some sort of a tension device, over a guide pulley 12, Fig. 1, and a "mackerel back" 13, into the 30 tank 2. The fabric then passes across one side of the suction tube 5, around the roll 4 and across the suction tube 6 to the squeeze rolls 14 and 15 which are located immediately above the tank. The feeding movement of the cloth through the tank may be 35 produced either by the action of the squeeze rolls or by the soaping machine into which the web travels immediately after leaving the dyeing machine.

40 As the cloth passes through the bath in the tank 2 a certain amount of the dye or color soaks into it, but the penetration of the dye into the cloth is greatly facilitated by the suction maintained in the tubes 5 and 6. That 45 is, as the web of cloth passes across the slots in these tubes it substantially closes these slots and the air pressure on the liquid in the tank forces this liquid through the cloth, the pressure so applied depending upon the 50 degree of vacuum maintained in the suction tubes. The surplus dye bath is squeezed out of the fabric as it passes between the rolls 14 and 15 and some additional penetration of the liquid into the fabric occurs at this 55 point. It has been definitely determined in actual mill practice that the machine produces a very superior penetration of the dye stuff in the fabrics which have proved very troublesome in this respect heretofore.

60 In this machine the fabric is alternately wet with the dye bath and then the liquid bath is sucked through it. The number of these alternate operations or steps may be varied in accordance with the nature of the 65 fabric, the consistency of the dye bath, and

other practical considerations. In some cases a single suction tube may be sufficient, and it is not always necessary or desirable to have the final suction applied to the goods while it is still submerged in the dye bath. In this machine provision has been made for duplicating the roll and suction tube arrangement at the opposite side of the tank. This modification is shown in Fig. 4 in which the roll 4 and suction tubes 5 and 6 are arranged exactly as in the construction shown in Fig. 2. It will be observed that the roll 4 is mounted in a pocket or depression in the left-hand side of the tank 2, and another such depression or pocket is made in the right-hand side of the tank. Another roll 4' and suction tubes 5' and 6' are located in the latter side of the tank, as clearly shown in Fig. 4, and the web W, as it leaves the tube 6, is guided over the tube 5', around the roll 4', and then across the tube 6', passing from the last named tube to the squeeze rolls 14 and 15.

70 It will be appreciated that the machine permits a very rapid and efficient handling of the goods in addition to producing a superior penetration, and that it provides for the convenient delivery of the goods to the next succeeding machine.

75 While I have herein shown and described a preferred embodiment of my invention, it will be understood that the invention may be embodied in other forms without departing from the spirit or scope thereof. For example, the slots in the vacuum tubes may be of other forms or may consist of a series 80 of holes, these variations, however, being equivalents of the slotted construction shown.

85 Having thus described my invention, what I desire to claim as new is:

1. In a dyeing machine, the combination 90 of a tank adapted to hold a quantity of dye bath, two parallel stationary suction tubes mounted in said tank closely adjacent to each other in position to be submerged in the dye bath, a roll in said tank located closely adjacent and parallel to said tubes but at a different elevation from them, additional guiding means cooperating with said roll and tubes to guide a web of cloth over one tube, around said roll, and then over the other tube, 95 each of said tubes having a slot therein arranged to be substantially closed by said web, and means for maintaining a partial 100 vacuum in both of said tubes.

105 2. In a dyeing machine, the combination 110 of a tank adapted to hold a quantity of dye bath, two parallel stationary suction tubes mounted in said tank closely adjacent to each other in position to be submerged in the dye bath, a roll in said tank located closely adjacent to and parallel with said tubes but positioned below the tubes, additional guiding devices cooperating with said roll and tubes to guide a web of cloth over one tube 115 around said roll and then over the other 120 tube.

125

tube, each of said tubes having a slot therein extending longitudinally thereof in the side adjacent to the opposite tube whereby both of said slots will be substantially closed by said web, and means for maintaining a partial vacuum in both of said tubes.

WILLIAM E. CAFFRAY.
